UNITED STATES PATENT OFFICE.

ABNER SHIRK, OF DECATUR, ILLINOIS.

MULTIPOWER SHEARS.

Application filed January 15, 1923. Serial No. 612,760.

To all whom it may concern:

Be it known that I, ABNER SHIRK, a citizen of the United States, residing at Decatur, in the county of Macon and State of Illinois, have invented a new and useful Improvement in Multipower Shears, of which the following is a specification.

My invention relates to multi-power shears, and is more particularly adapted for tools of the type generally known as snips.

One of the important objects of the invention is to provide means for progressively increasing the multiplication of power between the handles and the blades as the cut approaches the points of the latter. In accomplishing this object, not only is the leverage on the movable blade progressively increased by increasing the distance between the power and the fulcrum, but the relative angular movement of the handle with respect to the pivotal movement of the blade progressively increases.

Another object of the invention is to provide improved means which constantly acts upon the movable blade to urge it into closer engagement with the fixed blade.

The invention will be better understood from the following detailed description taken in connection with the accompanying drawing which illustrates the preferred structure by means of which the invention is carried out.

In the drawing:—

Fig. 1 is a side elevation of the invention.

Fig. 2 is a perspective view thereof.

Fig. 3 is a transverse section taken on the line 3—3 of Fig. 1.

Fig. 4 is a transverse section on the line 4—4 of Fig. 1.

The invention comprises a pair of blades 5 and 6, which are pivotally connected at 7. The blade 5, which is relatively fixed, when the tool is in use, is extended beyond its pivot to form a comparatively long shank 8 and a handle 9 integral therewith, which is adapted to be engaged by the fingers of the operator. The other blade 6 is extended to form a comparatively short shank 10 which is provided with a curved slot 11. The handle 12, which is adapted to be engaged by the thumb of the operator, is provided with a shank 13 having forwardly and inwardly extending ears 14 and 15 that extend on either side of the shank 8, and are pivotally connected thereto by

means of a pivot pin 16. The ears 14 and 15 are extended on the opposite sides of the shank 13, as indicated at 17 and 18, to form in effect a bifurcated arm which carries a roller 19 that engages the slot 11 and travels back and forth in said slot when the handles are operated to actuate the blades 5 and 6.

As the handle 12 is moved about its pivot 16, power is applied to the shank 10 of the blade 6, by means of the roller 19 traveling in the slot 11, and as the cut approaches the outer ends of the blades, the point of application of the roller 19 travels away from the pivot 7 and thereby increases the leverage on the shank 10. It will also be noted that the slot 11 is curved with its concaved side toward the fixed shank 8, and the radius of curvature of said slot progressively increases toward the end nearest the handle so that as the blades approach closed position and the cut progresses toward the points thereof, the relative angular movement of the handle with respect to the angular movement of the blade 6 will be increased. Thus, the angle between the path of the roller and the direction of the slot at the beginning of the cut is about 45 degrees, and toward the end of the cut is about 10 degrees, which further increases the power which may be applied to the blades as they approach the end of the cut.

In order to insure close engagement of the blades with each other and thereby to adapt the shears to the cutting of thin metal and paper and the like, as well as to the cutting of metal of heavy gage, the shank 10 is offset beyond the pivot 7, as shown at 20, so that the shank 10 is in substantially the same plane as the shank 8. A flat spring 21 is clamped on the pivot pin 7 between the nut 22 and the blade 5 and bears on the shank 10, in rear of its pivot, with sufficient force to maintain a close engagement between the blades, as will be readily understood.

From the foregoing description, it will be seen that I have provided a simply constructed tool which may be used to advantage in cutting any kind of sheet material, from the lightest to the heaviest. The cutting may be done more easily and more rapidly by reason of the progressive increase of the power as the cut approaches the points of the shears.

While I have described what is at present the preferred form of my invention, it will

be understood that this is merely illustrative, and that various modifications may be made therein without departing from the spirit of the invention. It will also be understood that the same principles may be used in connection with other tools having pivoted jaws, such as pliers or the like, and that the invention includes all such equivalents as may fall within the scope of the appended claims.

What is claimed is:—

1. A pair of shears provided with a relatively fixed blade having a shank terminating in an integral handle, a relatively movable blade intermediately pivoted thereto and having a relatively short shank, a second handle having a shank with ears secured to opposite sides thereof and extending inwardly and outwardly therefrom, the inwardly extending portions straddling the first-mentioned shank and connected thereto by a pivot pin, the outwardly extending portions of the ears having a roller journaled between them, said short shank having a curved slot in which said roller rides, said slot extending at a progressively increasing distance from said pivot pin.

2. A pair of pivoted coacting blades having shanks extending beyond the pivot, one of said shanks having an integral handle, the other shank terminating short of the handle and provided with a curved slot, a second handle having a shank terminating in a pair of ears which are pivoted to opposite sides of the shank of the first-mentioned handle, said ears also extending laterally in the opposite direction and carrying a roller engaging said slot.

3. A pair of shears including a fixed blade, a movable blade pivoted thereto, the fixed blade having an integral handle, a second handle pivoted to the shank of the fixed handle, said movable blade having a shank terminating short of the pivot of the movable handle and having a curved

slot with its concave side toward said pivot but eccentric thereto, said movable handle having means engaging said slot, the curvature of said slot increasing in radius toward the handle whereby increased power is obtained as the cut approaches the point of the shears.

4. A pair of shears including a fixed blade, a movable blade pivoted thereto, the fixed blade having an integral handle, a second handle pivoted to the shank of the fixed handle, said movable blade having a shank terminating short of the pivot of the movable handle and having a curved slot with its concave side toward said pivot but eccentric thereto, said movable handle having a laterally extending arm and a roller carried by said arm and engaging said slot, the curvature of the slot increasing in radius toward the handle whereby greater power is obtained as the cut approaches the point of the shears.

5. A pair of shears including pivoted blades provided with handles for actuating the same, and a flat spring secured to the pivot outside of one of the blades and bearing against the shank of the other blade between the pivot and the handle in a direction transverse to the movement of the blades to urge the cutting edges together.

6. A pair of shears including pivoted blades having shanks extending beyond the pivot and provided with handles, one of the shanks being offset in rear of the pivot, said offset portion being in the same plane as the shank of the other blade, and a flat spring secured to the pivot outside of the last-mentioned blade and bearing against the offset shank portion in a direction transverse to the plane of movement of the blades to urge the cutting edges together.

In testimony that I claim the foregoing as my own, I have hereto affixed my signature.

ABNER SHIRK.
